SPINNING TOP

Peter N. Chiarle, Kansas City, Mo.

Application March 15, 1954, Serial No. 29,505

Term of patent 3½ years

(Cl. D34—15)

Fig. 1.

Fig. 2.

Fig. 3.

To all whom it may concern:

Be it known that I, Peter N. Chiarle, a citizen of the United States, residing at Kansas City, Jackson County, State of Missouri, have invented a new, original, and ornamental Design for a Spinning Top, of which the following is a specification, reference being had to the accompanying drawing, forming part thereof, in which:

Fig. 1 is a plan view of a spinning top embodying my new design;

Fig. 2 is a side elevational view of same; and

Fig. 3 is a bottom view of same.

I claim:

The ornamental design for a spinning top, as shown.
